UNITED STATES PATENT OFFICE.

LOUIS KELLNER, OF CHICAGO, ILLINOIS, ASSIGNOR TO CHICAGO FUSE MFG. COMPANY,
OF CHICAGO, ILLINOIS, A CORPORATION OF ILLINOIS.

SWITCH.

Application filed April 27, 1925. Serial No. 26,007.

The invention relates to improvements in switches, particularly snap switches adapted to be used in electric lighting circuits.

The primary object of the invention is to provide a novel snap switch for electric circuits which is compact and small in size thereby being adapted to be mounted in shallow outlet boxes, but which is also efficient and certain in operation.

10 A more specific object is to provide a new and improved switch for electric circuits in which the movable contact element is given a rectilinear movement instead of the usual curvilinear movement, thereby resulting in 15 a shorter actual travel without a reduction in the break distance, and resulting in a reduction of the space required, in height and in depth.

Still other objects are to provide switches 20 of the above character which can be installed with standard parts, such as standard cover plates and fastening brackets for the outlet boxes, which are adapted to be actuated either by push buttons or by toggle buttons 25 and can be changed from one to the other by a mere substitution of buttons, and which can be made into either single pole switches, double pole switches or three-way switches without a substantial change in the operating mechanism.

Further objects and advantages will become apparent as the description proceeds.

In the accompanying drawings, Figure 1 is a vertical sectional view of an outlet box 35 secured in a vertical wall, and having a switch embodying the features of my invention mounted therein.

Fig. 2 is a sectional view of the switch taken along line 2-2 of Fig. 3.

40 Fig. 3 is a front view of the switch.

Fig. 4 is a sectional view taken along line 4-4 of Fig. 3.

Fig. 5 is a fragmentary sectional view of the switch operating mechanism taken along 45 line 4-4 of Fig. 3, the mechanism being shown in one position of rest.

Fig. 6 is a view similar to Fig. 5 but showing the mechanism about to snap into the position shown in Fig. 5.

50 Fig. 7 is a perspective view of the contact terminals for a double pole switch.

Fig. 8 is a similar view of the contact terminals for a three-way switch.

Fig. 9 is a front view of a modified form

of the switch in which a toggle actuator 55 is substituted for the push button actuator.

Fig. 10 is a side view partially in section thereof.

Fig. 11 is a front view of a single pole switch adapted to be actuated by push buttons.

Fig. 12 is a perspective view of the main parts of the operating mechanism in disassembled relation.

While the invention is susceptible of various modifications and alternative constructions I have herein shown the preferred embodiments thereof, but it is to be understood that I do not thereby intend to limit the invention to the specific forms disclosed but 70 aim in the appended claims to cover all modifications and alternative constructions falling within the spirit and scope of the invention.

Referring to the drawings, 13 represents 75 a shallow outlet box adapted for use in thin walls, and in the present instance secured to a wall 14 by end brackets 15 (see Fig. 1). A conduit 16 for lead wires (not shown) extends through a hole 17 in the upper end 80 wall of the box 13, and is rigidly secured thereto by an outer lock nut 18 and an inner threaded bushing 19. A switch 20 embodying the features of my invention is mounted in the box 13 by means of a yoke 21 which 85 is secured at its opposite ends to lugs 22 struck out from the upper and lower edges of the box. The front of the box is closed by a suitable cover or face plate 23 which fits against the wall 14, and which is secured by screws 24 to the yoke 21. By mounting the conduit 16 in the upper wall instead of the rear wall of the box 13, the required depth of the box is decreased by 90 the lateral space which would have been taken up by the bushing 19, but the available vertical space is correspondingly reduced. By making the switch 20 compact and consequently small in size, the box 13 can be of standard height, thereby permitting 100 the brackets 15 and the cover plate 23 to be standard in construction.

The switch 20 comprises a hollow base 25 of any suitable insulating material such as porcelain, and open at one side, which is 105 closed by a fibre cover 26 and which is secured to the yoke 21 by screws 27.

A plurality of fixed contact terminal are

provided having plates 28 which are secured to opposite sides of the upper and lower front edges of the base 25, and which are provided with binding screws 29 for attaching the lead wires (not shown) extending from the conduit 16. These terminals are provided with fingers or blades varying in shape and arrangement as desired to constitute the fixed contacts of either a single pole switch, a double pole switch or a three-way switch.

In the double pole switch, two sets of terminals (see Fig. 7) are provided which are similar in shape and arrangement but opposite or reversed in form. The single pole switch (see Fig. 11) comprises but one of these sets of terminals. Each set of terminals consists of an arm 30 extending from one of the lower plates 28 into the base 25 and along the rear wall to the upper end thereof, and having its end bent back on itself to form a contact blade 31, and of a contact blade 32 extending directly from the corresponding plate 28 at the upper end of the base into lateral alignment with the first blade. The two sets of terminals in the double pole switch thus are located at opposite sides and in the upper end of the base 25.

The three-way switch (see Figs. 3, 4 and 8) also comprises two sets of terminals, one set of which is identical with either set in the double pole switch. The other set of terminals consists of a vertical arm 33 on one of the lower plates 28, and the end of which constitutes a contact blade, and an arm 34 connected to the corresponding upper plate 28 by a bar 35 projecting into the base 25, said last mentioned arm extending downwardly along the rear wall of the base. The end of the arm 34 is bent to form a blade 36 directly back of and in line with the end of the arm 33. Thus, in the three-way switch the two sets of terminals are located respectively at the upper end and substantially midway of the ends of the base 25, and at opposite sides thereof. The upper plates 28 in the three-way switch are electrically connected by a connecting plate 37. Opposite sides of the end of each terminal blade in each switch are chamfered.

Mounted in the base 25 is a switch operating mechanism (see particularly Figs. 5, 6 and 12) which comprises a frame 38 rigidly secured to the rear wall of the base by screws 39, and a clip carrier 40 in the form of a slide reciprocable in said frame. The upper and lower edges of the slide are formed with notches 41 adapted to fit around the screws 39 as the slide is moved from one extreme position into the other. A pair of lugs 42 struck up from the back of the frame 38 extend through two longitudinal slots 43 in the carrier slide 40, and are pro-

vided at their free ends with hooks 44 engaging the outer edges of said slots. The lower ends of the slots 43 are formed with lateral extensions 45 adapted to pass over the hooks 44 thereby permitting the slide 40 to be removed from the frame when desired. A pair of lugs 46 are struck in, one from each side of the upper end of the frame 38, and engage opposite sides of the slide 40. The lugs 42 and 46 serve to hold the slide 40 in operative relation against the frame 38.

The upper end of the slide 40 is provided with two lateral and oppositely extending arms 47, the outer ends of which are provided with shoulders 48. Fitting against the shoulder on each arm 47 is a metal washer 49. An insulating sleeve 50 is positioned on the arm next to the washer 49 and a pair of insulating washers 52 are positioned on the sleeve. Two conducting strips, preferably copper and bent apart at their ends to constitute a pair of spring contact clips 51 are mounted on the sleeve 50 between the washers 52. A metal washer 53 is positioned on the arm 47 next to the outer washer 52 and the extreme end of the arm is riveted to hold the parts rigidly in assembled relation.

The clips 51 on each arm are adapted to engage one set of terminals. In the single pole switch, only two clips 51 on one arm are therefore required and provided. In the double pole switch, the clips serve to open or close both sets of contact terminals simultaneously, while in the three-way switch the clips are adapted to close one set of terminals in one position of the slide 40 and the other set of terminals in the other position of the slide.

A rocker member 54 is provided having a pair of ears 55 and 56 which are secured to a spindle 57. Opposite ends of the spindle 57 are journaled in a pair of standards 58 and 59 extending forwardly from opposite sides of the frame 38. Wound around the spindle 57 between the ears 55 and 56 is a heavy coil spring 60, the opposite ends of which extend inwardly past opposite edges of the rocker member 54 into engagement with opposite sides of a lug 61 struck up from the center of the slide 40, and tend to move said slide in opposite directions.

The rocker member 54 is provided at opposite sides with a pair of forwardly inclined arms 62 each of which has a longitudinal slot 63, and which are adapted to be oscillated by either a pair of push buttons 64 (see Figs. 1 to 6 and 11) or a toggle button 65 (see Figs. 9 and 10). The buttons 64 and 65 are made of insulating material, such as formed hard rubber, and extend through suitable openings 66 and 67 in the yoke 21 and the cover plate 23 respectively.

Each push button 64 preferably is pro-

vided with a plate 68 imbedded therein, and having a sliding and rotative connection with one of the rocker arms 62. To this end, the plate 68 is formed with a slot 69 open at 5 one end and fitting over the end of the rocker arm, the slot 63 in the latter providing clearance for the edges of the slot 69 as the button 64 is reciprocated. Where a toggle button 65 is used, the arms 62 of the 10 rocker member 54 are preferably molded in the matrix of the spaced arms on the button thereby forming a rigid connection.

To hold the slide 40 in one position or the other until actuated or snapped by the 15 proper button, one edge thereof is formed with a pair of spaced notches 70 and 71 adapted to be engaged by a lug 72 on a locking member 73. The locking member is 20 slidably disposed in a slot 74 in the standard 59, and is normally pressed by a spring 75 to move the lug 72 into one of the notches 70 and 71. The spring 75 in the present instance comprises a wire, the fixed end of 25 which is anchored in the frame 38 and engages a lug 76 struck out from said frame, and the free end of which fits into a notch 77 in the outer edge of the locking member 73 and tends to move the latter outwardly.

A cam block 78 is secured to the inner 30 edge of the locking member 73, and has a pair of lateral extensions 79 which are adapted to be alternately engaged by a pair of trip arms 80 formed on opposite sides of the adjacent ear 56 to permit the spring 35 60 to shift the slide 40. The arms 80 are also adapted to engage a pair of lugs 81 struck in from the sides of the outer end of the adjacent end standard 59 to limit the rotation of the rocker member 54 on the spindle 57.

The operation briefly stated is as follows: When the slide 40 is in the position of rest shown in Fig. 4 both sets of terminals are bridged by the clips 51 on the arms 47, and 45 the slide is locked against movement by the lug 72 engaging in the notch 71. To snap the switch the outermost push button 64 is pressed inwardly (or the toggle button 65 is actuated), thereby oscillating the rocker member 54. Since the slide 40 is held against movement by the locking member 73, the rocker member 54 will separate the ends of the spring 60 as shown in Fig. 6, thereby storing potential energy into said spring to 55 subsequently snap the switch. When the rocker member has been oscillated through a certain distance, one of the trip arms 80 will engage one of the lugs 79 on the locking member 73, and thereby move the latter rearwardly against the force of the spring 75 to disengage the slide 40. The end of the spring 60 in engagement with the lug 61 will thereupon snap the slide 40 with considerable force into the position shown in Fig. 5. 60 Upon releasing the push button 64, the rock-

er member 54 is re-positioned to permit the locking member 73 to move into its normal position, so that as the slide 40 is moved into the position shown in Fig. 5, the lug 72 will engage the notch 70 to hold the slide in 75 open position until actuated again. In the single and double pole switches, all the terminals will be open, while in the three-way switch, the blades 31 and 32 will be open and the blades 33 and 36 will be bridged.

It will be evident that I have provided an advantageous switch adapted for electric circuits which is simple in construction and operation, and which by virtue of such construction and particularly the rectilinear movement of the movable contact means is compact and small in height and depth, thereby adapting it to shallow outlet boxes of standard height usually mounted in thin walls. While the size is reduced by reason 80 of the rectilinear movement of the movable contact means no shortening of the break distance results. The switch can be adapted to be used as either a single pole switch, a double pole switch or a three-way switch 85 merely by rearranging the fixed contact in the base 25, and without any change in the construction of the operating mechanism except the elimination of one of the arms 47 in the single pole switch. The switch can 90 also be adapted to be operated by push button actuators or by a toggle actuator without any changes in the construction in addition to the mere substitution of the actuator.

I claim as my invention:

1. A switch having, in combination, a base having a set of contact terminals fixed therein, a frame mounted in said base, a carrier reciprocably mounted in said frame and having clip means adapted to engage said terminals in one position of said slide, a rocker member pivotally mounted in said frame, a coil spring adapted to be actuated by said rocker member to reciprocate said carrier, a locking member slidably mounted on said frame and adapted to lock said carrier in each position until said rocker member has been oscillated through a predetermined extent, and means for oscillating said rocker member.

2. A switch having, in combination, a base having a set of contact terminals fixed therein, a frame mounted in said base, a carrier slide reciprocably mounted in said frame, means on said slide for engaging or disengaging said contact terminals when moved into different positions, means slidably mounted on said frame for engaging said slide to hold said slide in said positions, pivotal means mounted in said frame for releasing the last mentioned means, and spring means controlled by said pivotal means for shifting said carrier slide from one position to another.

3. A switch having, in combination, a

- base having a set of terminals therein, a frame mounted in said base, a carrier slide reciprocably mounted in said frame and having two positions of rest, said slide having two spaced notches in one side edge, contact means carried by said slide, said contact means being adapted to engage said terminals in one position of said slide and to be remote therefrom in the other position of 5 said slide, said slide having a lug, a coil spring mounted in said frame, the opposite ends of which are adapted to engage opposite sides of said lug, means having a lug adapted to selectively engage said notches 10 to hold said slide in either position of rest, and means for separating the ends of said spring to store energy therein for shifting said slide, and for releasing said last mentioned means to permit said spring to shift 15 said slide.
4. The combination in a switch, of two relatively movable parts, a locking member slidably mounted in one of said parts and adapted to engage the other of said parts to lock said parts against relative movement, spring means tending to move said locking member into locking engagement, spring means mounted on one of said parts and engaging the other of said parts, means for 20 storing energy in said last mentioned spring means, the latter when under stress tending to move said parts relatively to each other, and means for tripping said locking means to permit said last mentioned spring means to effect said relative movement.
5. A switch having, in combination, a base having a plurality of fixed contact terminals, a frame secured to the inner wall of said base and having lateral forwardly projecting standards, the back of said frame being formed with a pair of hooks and with 25
- 30
- 35

a pair of inclined lugs in opposite sides, a slide formed with a pair of longitudinal slots having lateral extensions at one end adapted to pass over said hooks, said slide being slidably disposed on said frame between said lugs with said slots engaging said hooks, contacts carried by said slide for movement into and out of engagement with said terminals, and means for actuating said 30 slide.

6. A switch having, in combination, a frame having a back and side standards extending forwardly thereof, one of said side standards having a longitudinal slot, a slide 55 mounted on said frame, said frame being formed with means for holding said slide in position, a locking member slidably disposed in said slot for movement into and out of locking engagement with said slide, a cam 60 block on said locking member, spring means for shifting said slide, means for actuating said spring means, and arms on said last mentioned means for engaging said cam block to release said slide for movement by 65 said spring means.

7. A switch having, in combination, a frame having a slot therein, a movable member disposed in said frame for movement in a line perpendicular to said slot, said member having a pair of spaced notches in one edge, a locking member slidably mounted in said slot and having a lug adapted to selectively engage said notches to hold said movable member in either of two positions, and 75 means for actuating said movable member, said last mentioned means having means for actuating said locking member to release said movable member.

In testimony whereof, I have hereunto af- 80 fixed my signature.

LOUIS KELLNER.
